UNITED STATES PATENT OFFICE.

ROBERT WALKER, OF DOVER, NEW JERSEY.

STRUCTURAL SLEEVE FOR FOUNDATION SILLS.

Application filed August 29, 1921. Serial No. 496,440.

To all whom it may concern:

Be it known that ROBERT WALKER, a citizen of the United States of America, residing at Dover, in the county of Morris and State 5 of New Jersey, has invented new and useful Improvements in Structural Sleeves for Foundation Sills, of which the following is a specification.

The object of the invention is to provide 10 a simple and efficient means for joining foundation sills and other structural timbers and affording seats in connection therewith for the terminals of intersecting beams to avoid the necessity of mortising the beams 15 thereinto, and at the same time to avoid the waste of timber and the loss of time incident to effecting such joints; and with this object in view the invention consists in a construction and combination of parts of 20 which a preferred embodiment is shown in the accompanying drawings; wherein:—

Figure 1 is a side view, and

Figure 2 is a plan view of a sill joining sleeve constructed in accordance with the 25 invention.

Figure 3 is an end view of the same showing the sill in section.

The device consists essentially of a sleeve 10 of plate metal, preferably wrought iron 30 or its equivalent of cross sectional dimensions adapted to receive the extremities of adjoining sill timbers 11 which are arranged with their ends in abutting relation at or about the center of the length of the sleeve 35 and are secured therein by transverse rivets 12 or similar fastening devices serving to prevent relative displacement and reinforce the joint, and carried by this sleeve may be one or more chairs or seats of which two, 40 shown respectively at 13 and 14 are illustrated in the drawing with lateral upstanding flanges 13^a and 14^a, for the reception of the adjacent extremities of timbers 15 and 16 arranged in intersecting planes with the 45 sills adjacent to the joint. The inner walls 13^b and 14^b of these chairs or seats are riveted or otherwise fastened as indicated at 17 to the side walls of the sleeve, and

obviously may be attached thereto at any desired portion of the length thereof according to the plane of intersection of the side timbers, and the latter are secured in the chairs or seats by rivets 18 or the equivalents thereof to prevent endwise or upward movement thereof.

The use of a joining member such as described while insuring the rigidity of the joints between the sill member and between the extremities of the beams and the sill, avoids the necessity of cutting away or mortising the sill ends or mortising the intersecting beams into the sills, with the further advantage that the intersecting timbers may be attached either directly opposite the joint between the sill members or at one side or the other thereof according to the demands of the structure, without weakening or affecting the joint between the sill members or between the beams and the sill members, and without necessitating any complicated cutting of the material.

Not only is the resulting joint equally as strong if not stronger than when a mortise connection is formed, but the waste of material incident to the overlapping of the timbers and the consequent cutting away thereof is avoided and a large part of the time occupied in forming the joints is saved.

Having described the invention, what is claimed as new and useful is:—

A steel structural joint comprising a parallelopiped sleeve which is open from end to end, a chair member applied to the side of the sleeve and formed from a sheet of metal having a bottom portion and side flanges which are spaced from each other above the bottom portion, said bottom portion and side flanges being provided with inturned and overlapping inner end flanges, and securing devices passing through the overlapping flanges and securing the chair member to the sleeve.

In testimony whereof he affixes his signature.

ROBERT WALKER.
